(57) **CLAIM**

The ornamental design for a packaging container, as shown and described.

DESCRIPTION

1. Packaging container

1.1 : Perspective

1.2 : Top

1.3 : Front

1.4 : Right

1.5 : Bottom

(Continued)

The present design is a packaging container; the container surface is provided with a geometric pattern consisting of adjacent triangularly inclined surfaces; the portion presented by solid lines is the claimed part; a rear view is the same as the front view; a left side view is the same as the right side view.
